Patented Dec. 7, 1926.

Des. 71,630

UNITED STATES PATENT OFFICE.

DEWEY C. WILSON, OF HERMLEIGH, TEXAS.

DESIGN FOR AN INCENSE BURNER OR SIMILAR ARTICLE.

Application filed July 10, 1926. Serial No. 18,305. Term of patent 7 years.

To all whom it may concern:

Be it known that I, DEWEY C. WILSON, a citizen of the United States of America, residing at Hermleigh, Texas, have invented a new, original, and ornamental Design for an Incense Burner or Similar Article, of which the following is a specification, reference being had to the accompanying drawing, forming part thereof.

The figure is a perspective view of an incense burner or similar article, showing my new design.

I claim:

The ornamental design for an incense burner or similar article, as shown.

DEWEY C. WILSON.
